UNITED STATES PATENT OFFICE

WILLIAM ANDERSON, OF CHICAGO, ILLINOIS

FILING MACHINE

Application filed August 9, 1930. Serial No. 474,833.

The present invention is related to machines for filing metals and other hard materials, and is more especially concerned with the machine illustrated, described and 5 claimed in my pending application for Letters Patent of the United States filed July 5, 1928, Serial No. 290,653.

The object of the present invention is to improve certain features of the machine referred to, having particularly in mind the mountings of the filing elements and the carrier for the same, whereby the machine is rendered more efficient and its durability and life increased.

15 In addition to the general object stated other objects will appear as the nature of the improvements is better understood, the invention consisting substantially in the novel construction, combination and arrangement 20 of parts hereinafter fully described, illustrated in the accompanying drawings, and finally pointed out in the appended claims.

In the drawings:

Fig. 1 is a front elevation of a filing machine embodying the present invention, the front of the machine casing being removed;

Fig. 2 is a fragmentary side elevation, on an enlarged scale, and partially in section, illustrating the relation of the upper and 30 lower guides to the table or work support;

Fig. 3 is a sectional plan view on the line 3—3, Fig. 2;

Fig. 4 is a side elevation of a portion of the file carrier, the filing elements being removed therefrom;

Fig. 5 is a similar view of the file carrier taken at right angles to the disclosure of Fig. 4;

Fig. 6 is a vertical sectional view on the line 6—6, Fig. 5;

Fig. 7 is an inverted sectional view on the line 7—7, Fig. 4;

Fig. 8 is a sectional plan view on the line 8—8, Fig. 5;

Fig. 9 is a detail perspective view of one of the file supports forming part of the file carrier;

Figs. 10 and 11 are similar views of the male and female connectors associated with 50 the file support disclosed in Fig. 9.

Referring now in detail to the accompanying drawings, the numeral 15 designates the supporting frame of the machine. It includes a base 16 by which the machine is secured to the surface on which it is to be placed, and also a head 17. Journaled for rotation in the frame 11 is a driving wheel 18, and adjustably mounted on the head 17 is an idler wheel 19. Power is applied to the driving wheel 18 from any suitable source.

The idler wheel 19 is adjustably mounted on the head 17 for movement towards and away from the driving wheel 18, any suitable mechanism, conventionally illustrated at 20, being employed for effecting this adjustment 65 of the wheel 19.

Trained over the wheels 18 and 19 is an endless carrier 21 for the filing elements. This carrier includes a series of elongated file supports 22, and each of said supports is 70 slotted at each of its ends, as at 23, said slots being open at one side, but closed at the side opposite thereto. Pivotedly mounted in one of said slots 23, is a male link member 25, the pivotal point of said member being in 75 proximity to the mid portion of the file support 22. The outer extremity of the male link member projects beyond the contiguous end of the file support 22, and is perforated in order to receive a pintle 26 which is also positioned in a forked head 27 carried by a female link member 28 associated with the immediately contiguous file support 22. Thus each two adjacent file supports 22 are 80 so connected as to readily flex or break joint 85 with respect to each other in the manner hereinafter described.

The female link members 28 are pivotally mounted in the slots 23 of the file supports 22 at the ends of said supports which are opposite to the slots in which the male link members 25 are pivotally mounted, said female link members being held in pivotal relation to the file supports 22 by the pintles 29. In the mounting of the female link members 28 within their respective slots the forked members 27 thereof project beyond the adjacent end of the file support, and in the swinging movement of the female link members with respect to their respective file 100

supports the forked members 27 thus are free for clearance with respect to these supports.

As thus constructed, the file carrier comprises a plurality of the file supports 22 which, in the vertical stretches of the carrier are longitudinally aligned, but which break joint as they pass around the wheels 18 and 19, thus permitting the carrier to flex with respect to the wheels and prevent its displacement from the wheels. Through the adjusting means 20 the proper degree of tension may be placed upon the carrier in the movement of the wheel 19 relatively to the wheel 18, thereby preserving the proper relation of the male and female link members with reference to the file supports 22, and likewise maintaining the alignment of the latter in relation to each other.

Each of the file supports 22, at points adjacent to the ends thereof, is provided with oppositely disposed openings 30 and 31. The openings 31 are of larger diameter than the openings 30, as clearly shown in Fig. 8, the purpose of this being to permit the passage of screws 32 through the openings 31 for positioning said screws in the openings 30 through which they pass for engagement with threaded openings 33 in the filing elements 34. The heads of the screws 32 fit snugly within the slots 23, the inner ends of the openings 30 being countersunk for this purpose, so that the heads of said screws are out of the path of the swinging movement of the links 25 and 28 and the latter are free from interference by the screws.

The file elements 34 may be of any suitable construction, the length of the same being such that the extremities project beyond the ends of the file supports 22 and overlap the projecting ends of the link members 25 and 28. In the vertical stretches of the file carrier the file elements are substantially aligned, their adjacent ends being in sufficient proximity to each other to present substantially a continuous surface in their passage over the work.

The base 16 has a work table or support 35 suitably connected thereto, and adjustable with relation to the base, as illustrated and described in my pending application Serial No. 290,653 hereinbefore referred to. This work table is perforated so that the file carrier and the filing elements mounted thereon may pass through said table. It is essential that the construction of the file carrier be such as to permit its separation at an appropriate point, in order to train the file carrier through the opening of the work table or support 35. To this end the pivotal connection of one of the male link members 25 is in the form of a removable pin 36, the construction of which appears in Fig. 7. One end of the pin 36 is grooved, as at 37, circumferentially of the pin, thereby providing a head 38 at the outer end of the pin 36. The

latter is provided with a rounded shoulder 39, and said shoulder is engaged by a bowed locking spring 40 that is seated in the body of the file support 22 which carries the removable pin 36. The spring 40 serves to prevent outward displacement of the pin 36, but it readily yields to such outward movement of said pin 36 when sufficient pull is exerted thereon to remove the pin 36 from the body of the file support 22. This permits the shoulder 39 to ride over the spring 40, and when said pin has been withdrawn the male link member 25 of which it serves as a pintle may be readily separated from the slot 23 of the file support 22 which it occupies, thus disconnecting the male link member 25 from said file support so as to free the file carrier for withdrawal from the opening of the work table or support 35.

In order to permit proper gripping of the removable pin 36 to withdraw the same from the file support 22 in which it is seated, the side of said support is provided with an elongated slot 41 that intersects the opening of the support which receives the pin 36. This slot 41 enables the introduction of a suitable tool to the rear of the head 38 of the pin, whereby to effect the desired pull on said pin to remove the same when such is desired.

The head 17 of the frame has a depending arm 42 which supports an upper guide designated generally by the numeral 43. A lower guide 44 of similar construction is carried by the base 16 of the frame 15, and is positioned beneath the work table or support 35 in vertical alignment with the upper guide 43. These guides are employed so that the file sections will be rigidly supported as they pass through the opening of the work table or support 35 and as the work thereon is pressed against the file elements. The construction of the upper and lower guides 43 and 44 is substantially the same, and this construction is clearly shown in Figs. 2 and 3, in which latter a sectional plan view of the upper guide is disclosed. The lower end of the arm 42 supports a guide plate 45 which is bolted or otherwise suitably fastened to said arm 42 as at 46. A vertical series of freely rotatable guide rollers 47 is arranged at the face of the arm 42, each of said rollers being held upon said arm by a headed stud 48 secured in the arm 42 by a set screw 49, and said rollers 47 are contacted by the file carrier 21 in its passage through the guide 43.

Also carried by the arm 42, and arranged at right angles to the rollers 47, is a vertical series of rollers 50, the latter also being held to the arm 42 through the medium of a series of headed studs 51 secured in place by set screws 52. The rollers 47 and 50 resist the movement of the file carrier 21 in planes at right angles to each other, thus insuring passage of the file elements to the work in a

rigid manner, and also resisting pressure of the work as the same is presented to the file elements.

A clamping block 53 also forms part of the upper guide, said block having a series of vertically aligned flanged rollers, 54 journaled thereon. The journal of each of said rollers is constituted by a headed stud 55 fitted into the clamping block 53 and held therein by a set screw 56. The flanges 57 of the rollers 54 are V-shaped and engage a V-shaped groove 58 formed at one side of each of the file supports 22 as these supports pass through the upper guide. The clamping block 53 is laterally movable, being guided in such movement by the guide plate 45, assisted by a pair of parallel guide fingers 59 which are received by corresponding recesses 60 formed in the arm 42. The movement of the clamping block 53 is controlled by an adjusting screw 61 having an operating head 62 at its outer end and a shouldered neck 63 adjacent thereto. The shank of the adjusting screw 61 is freely rotatable in the block 53, a clamping collar 64 being carried by said shank, and between said collar and the shouldered neck 63 is fitted the clamping block 53 so that in the movement of the screw 61 the block 53 will be caused to move therewith towards and away from the arm 42. By proper adjustment of the screw 61 the flanged rolls 54 are caused to approach the file carrier or be moved away from the same, and when properly presented to the file carrier the V-shaped flanges 57 of the rolls 54 will enter the V-shaped groove 58 of the file supports, and thus establish additional guiding means for movement of the file carrier in relation to the guide.

The lower guide 44, as above indicated, is of the same construction as the upper guide 43. By reason of being positioned beneath the work table or support 35 the lower guide is somewhat more inaccessible than the upper guide, and adjustment of the clamping block 53 thereof is somewhat less convenient. To overcome this the shank of the adjusting screw 61 is elongated so that the operating head 62 thereof will project beyond the work table or support 35 to be easily grasped by the operator and manipulated when it is desired to adjust the clamping block 53 of the lower guide in relation to the file carrier.

The wheels 18 and 19, and all portions of the file carrier save the portion between the upper and lower guides 43 and 44 and said guides, are enclosed in a casing or housing 65 of sectional construction, the sections thereof being hinged together. This conceals the moving parts of the machine, with the exception of the portion of the file carrier between the guides 43 and 44 and the guides from possible contact by the operator and injury of the latter in the movement of these parts.

In the operation of the herein described

machine, the work to be filed is supported by the work table or support 35. It is moved towards the file carrier and the filing elements 34 mounted thereon. As the filing elements pass the work, the latter being presented for contact with the filing elements, a cutting action ensues until the work has been reduced to the desired extent.

If it be desired to file the interior of the object under treatment, the pin 36 is removed so as to separate the file carrier at that point. One end of the carrier is then passed through the work, the pin 36 is replaced so as to connect the contiguous portions of the carrier, whereupon the machine may be set in operation and filing of the interior of the object under treatment effected.

I claim:

1. In a machine of the class described, the combination with a driving wheel and a driven wheel, of a flexible carrier supported by said wheels and including a plurality of file supports, a filing element connected to said file supports in a plane parallel to the plane of said flexible carrier, link connections pivotally mounted in said supports, whereby to permit the carrier to flex in its passage about the wheels, but to maintain said supports in alignment in the stretches between the wheels, a work support, and means oppositely disposed with respect to said filing elements for bracing said carrier to maintain the file supports in rigid relation to the work on said support as the file supports pass the same.

2. In a machine of the class described, the combination with a driving wheel and a driven wheel, of a flexible carrier supported by said wheels and including a plurality of file supports, each of said supports being provided with open sided slots extending from the ends of the supports inwardly adjacent their central portion, link connections mounted in said slots and joining adjacent supports, the ends of said link connections being pivoted to said file supports adjacent their central portion, whereby to permit the carrier to flex in its passage about the wheels, but to maintain said supports in alignment in the stretches between the wheels, and a work support for sustaining the work in the presentation thereof to the file supports.

3. In a machine of the class described, the combination with a driving wheel and a driven wheel, of a flexible carrier supported by said wheels and including a plurality of file supports, file elements mounted on a plane side of said file supports, each of said supports being provided with open sided slots, link connections pivotally mounted in said slots and joining adjacent supports, whereby to permit the carrier to flex in its passage about the wheels, but to maintain said supports in alignment in the stretches between the wheels, a work support, and means oppositely disposed with respect to said filing ele-

ments for bracing said carrier to maintain the file supports in rigid relation to the work on said support as the file supports pass the same.

- 5 4. In a machine of the class described, the combination with a driving wheel and a driven wheel, of a flexible carrier supported by said wheels and including a plurality of file supports, each of said supports being provided with open sided slots, link connections pivotally mounted in said slots, the link connections of each file support being pivotally connected to the latter adjacent the mid portion thereof and having their free extremities 10 positioned in the outer ends of the slots of the support, whereby to permit the carrier to flex in its passage about the wheels, but to maintain said supports in alignment in the stretches between the wheels, a work support, and means for maintaining the file supports in rigid relation to the work on said work support as the file supports pass the same.

- 5 5. In a machine of the class described, the combination with a driving wheel and a driven wheel, of a flexible carrier supported by said wheels and including a plurality of file supports, each of said supports being provided with open sided slots, a filing element detachably connected to each of said file supports, fastening means for said filing elements located at one side of said slots and accessible through the opposite side thereof, link connections pivotally mounted in said supports, whereby to permit the carrier to flex in its passage about the wheels, but to maintain said supports in alignment in the stretches between the wheels, and a work support for sustaining the work in the presentation thereof to the file supports.

- 40 6. In a machine of the class described, the combination with a driving wheel and a driven wheel, of a flexible carrier supported by said wheels, a series of treating elements mounted on said carrier and adapted to break joint with each other as they pass over the wheels, a work support adjacent to the path of movement of said carrier for sustaining the work in its presentation to the treating elements, and means for guiding the treating elements in their movement relatively to the work, said means including a series of rollers designed to engage the treating elements at one face, a second series of rollers designed to engage the treating elements at right angles to the engagement of the first mentioned rollers and clamping means for holding the treating elements in contact with said rollers in the passage of the treating elements relatively to said rollers.

- 60 7. In a machine of the class described, the combination with a driving wheel and a driven wheel, of a flexible carrier supported by said wheels, a series of treating elements mounted on said carrier and adapted to break joint with each other as they pass over the

wheels, a work support adjacent to the path of movement of said carrier for sustaining the work in its presentation to the treating elements, and means for guiding the treating elements in their movement relatively to the work, said means including a series of rollers adapted to engage the treating elements at one face, a second series of rollers designed to engage the treating elements at right angles to the engagement of the first mentioned rollers, a clamping block for holding the treating elements in contact with said rollers in the passage of the treating elements relatively to said rollers, and a series of flanged rollers carried by said clamping block and engaging the treating elements to maintain the latter in proper engagement with the first and second series of rollers.

8. In a machine of the class described, the combination with a driving wheel and a driven wheel, of a flexible carrier supported by said wheels, a series of treating elements mounted on said carrier and adapted to break joint with each other as they pass over the wheels, a work support adjacent to the path of movement of said carrier for sustaining the work in its presentation to the treating elements, and means for guiding the treating elements in their movement relatively to the work, said means including a series of rollers adapted to engage the treating elements at one face, a second series of rollers adapted to engage the treating elements at right angles to the engagement of the first mentioned rollers, a clamping block for holding the treating elements in contact with said rollers in the passage of the treating elements relatively to said rollers, and a series of flanged rollers carried by said clamping block and engaging the treating elements to maintain the latter in proper engagement with the first and second series of rollers.

9. In a machine of the class described, the combination with a driving wheel and a driven wheel, of a flexible carrier supported by said wheels, a series of treating elements mounted on said carrier and adapted to break joint with each other as they pass over the wheels, a work support adjacent to the path of movement of said carrier for sustaining the work in its presentation to the treating elements, guides for the treating elements arranged above and below the work support and serving to guide said elements in their movement relatively to the work, each of said guides including a series of rollers adapted to engage the treating elements at one face, a second series of rollers adapted to engage the treating elements at right angles to the engagement of the first mentioned rollers, and clamping means for holding the treating elements in contact with said rollers in the pas-

sage of the treating elements relatively to said rollers.

10. In a machine of the class described, the combination with a driving wheel and a driven wheel, of a flexible carrier supported by said wheels, a series of treating elements mounted on said carrier and adapted to break joint with each other as they pass over the wheels, a work support adjacent to the path 10 of movement of said carrier for sustaining the work in its presentation to the treating elements, guides for the treating elements arranged above and below the work support and serving to guide said elements in their 15 movement relatively to the work, each of said guides including a series of rollers adapted to engage the treating elements at one face, a second series of rollers adapted to engage the treating elements at right angles to the 20 engagement of the first mentioned rollers, a clamping block for holding the treating elements in contact with said rollers in the passage of the treating elements relatively to said rollers, and a series of flanged rollers 25 carried by said clamping block and engaging the treating elements to maintain the latter in proper engagement with the first and second series of rollers, the treating elements being provided with grooves adapted to receive the 30 flanges of said rollers as the treating elements pass said rollers.

11. In a machine of the class described, a continuous carrier, a series of treating elements mounted on said carrier, a work support adjacent to the path of movement of 35 said carrier, a series of rollers engaging the carrier at one side, and a second series of rollers engaging the carrier at an angle to the engagement of the first mentioned rollers.

40. 12. In a machine of the class described, in combination, a continuous carrier, a series of treating elements mounted on said carrier, a work support adjacent to the path of movement of said carrier, a series of rollers engaging 45 the carrier on the side opposite said treating elements, a second series of rollers engaging the carrier at right angles to the engagement of the first mentioned rollers, and means for holding said carrier against 50 said rollers.

13. In a machine of the class described, the combination with a driving wheel and a driven wheel, of a flexible carrier supported by said wheels and including a plurality of 55 file supports, filing elements connected to one side of said supports and positioned in a plane parallel to the plane of said flexible carrier, the working faces of said filing elements being presented to the work perpendicularly to the plane of the carrier, means on the side of said carrier opposite to said filing elements for bracing said carrier, and links 60 pivotally mounted in each of said supports and connected to the links of adjacent supports.

14. In a machine of the class described, the combination with a driving wheel and a driven wheel, of a flexible carrier supported by said wheels and including a plurality of file supports, each of said supports being provided with oppositely-extending open-sided slots, filing elements connected to one side of said supports and positioned in a plane parallel to the plane of said flexible carrier, the working faces of said filing elements being presented to the work perpendicularly to the plane of the carrier, bracing means for said carrier on the side opposite said filing elements, and oppositely-extending links pivotally mounted in the slots of each of said supports and connected to the links of adjacent supports.

In testimony whereof I have hereunto subscribed my name.
